UNITED STATES PATENT OFFICE.

HEINRICH BOCKISCH, DECEASED, LATE OF POUGHKEEPSIE, NEW YORK; BY GEORGE W. GITTINS, ADMINISTRATOR, OF NEW YORK, N. Y., ASSIGNOR TO WELTE-MIGNON CORPORATION, OF NEW YORK, N. Y., A CORPORATION OF NEW YORK.

TEMPO SIGNAL FOR SYNCHRONIZERS.

Application filed April 21, 1920. Serial No. 375,578.

To all whom it may concern:

Be it known that HEINRICH BOCKISCH, deceased, late a citizen of the Republic of Czechoslovakia, and formerly residing at Poughkeepsie, in the county of Dutchess and State of New York, United States of America, invented certain new and useful Improvements in Tempo Signals for Synchronizers, of which the following is a specification.

This invention relates to synchronizers and signals to indicate relative speed of parts. An exemplification of a synchronizer to which this invention may be applied is shown in the inventor's prior Patent #1,279,640, September 24, 1918.

The primary object of this invention is the provision of means for signalling the operator when the hand speed control means, of one of the devices to be synchronized, has been set in a position to operate the same too fast or too slow to be controlled efficiently by the synchronizer.

This invention is carried out when for example, it is applied to a synchronizer for an automatic musical instrument and a phonograph, by the provision of connections to the acceleration and retarding devices whereby a signal will be given when one actuates abnormally fast, thus indicating that the device giving the signal is being overtaxed and that the general controlling device should be set for a slower or faster speed as the case may be.

Referring to the drawings:—

Figure 1 is a diagrammatic view of the indicating signal device.

Fig. 2 is a plan view of a speed control device showing signals mounted adjacent thereto.

Like reference characters refer to similar parts in the different views.

In this specification the invention will be described as applied to a synchronizer for controlling the relative speeds between an automatic piano and a phonograph, although it may be applied to other devices.

10 designates the rail of an automatic musical instrument as a piano, 11 the controlling handle for regulating the speed when not using the synchronizer and for setting the general speed controlling devices so that the synchronizer may operate to control the relative speed of the two devices. 12

and 12' are signals which in the illustrated embodiment are small electric lights which show through the openings 13, 13' of the plate 14 mounted on the rail 10 and over the recess 15. The electric lights 12, 12' are mounted in the recess 15 and have suitable connections to a battery 16. In the circuit of the lamp 12 is a contact switch 17 controlled by a suitably actuated pneumatic 93; and in the circuit of the lamp 12' is a contact switch 18 controlled by the pneumatic 95.

The movable board of the bellows 93 carries a contact bridging element 97 and the movable board of the bellows 95 carries a contact bridging element 98. These elements when operated by the respective bellows 93 and 95, open and close circuits which cause mechanism to operate and slow down or speed up the automatic musical instrument.

Let us assume that when the pneumatic 93 is actuated it tends to slow down the speed of the automatic musical instrument and that when the pneumatic 95 is operated it tends to speed up the automatic musical instrument. The pneumatics 93 and 95 have respectively contact making members 93' and 95' which cause the switches 17 and 18 to operate respectively.

Suppose the controlling handle 11 is left too far toward one side so that the synchronizing mechanism is unable to quickly operate the speed control devices to synchronize the movements of the two devices. While the control pneumatic 95 is unable to speed up the piano fast enough, it operates up and down very fast, each time closing the switch 18 and lighting the lamp 12'. The circuit for the lamp is made as follows: From the positive side of the battery 16 by wires a, b', switch 18, wire c', lamp 12', bus bar d, wire e to battery 16. This flashing of the lamp 12' indicates to the operator that he should move the handle 11 in the direction of "faster" until the lamps alternate in flashes.

In case the control handle 11 is left too far toward the other extremity, the slowing down pneumatic 93 will operate and by its contact making member 93' operate the switch 17 to flash the lamp 12. The circuit to the lamp 12 is made as follows: From the battery 16 by wires a, b, switch 17, wire c to lamp 12, bus bar d, wire e to battery 16. This flashing of the lamp 12 indicates that

the control handle 11 should be moved in the direction of "slower" until the lamps flash alternately which is the indication that the proper point has been reached.

5. If prompt action is not taken in adjusting the speed control (tempo) device the synchronism will be incorrect and a new start will be necessary. By this invention it is clear that the readjustment may be quickly 10 made and much time and inconvenience can be saved.

While this invention has been described in connection with a particular form of synchronizer it will be clear that it is equally 15 adaptable to other synchronizers having movable parts to respectively cause relative slower and faster movements of the devices to be synchronized.

It is equally clear that modifications and 20 changes may be made within the spirit of the invention and the scope of the appended claims.

Having described my invention, what I 25 claim is:—

25 1. An attachment for a synchronizer having a speeding-up member and a slowing-down member, comprising a signal operatively connected to the speeding-up member and another signal operatively connected to the slowing-down member.

30 2. An attachment for a synchronizer having a speeding-up member and a slowing-down member, comprising signals operatively electrically connected respectively to the speeding-up and slowing-down members.

35 3. An attachment for a synchronizer having a speeding-up member and a slowing-down member, comprising a switch operated 40 by the speeding-up member, a switch oper-

ated by the slowing-down member, signals electrically connected to each of the switches and a source of electrical energy in the circuit with the switches and signals, to operate the latter upon operation of the former. 45

4. In combination, a synchronizer having means for speeding up and means for slowing down one of the parts to be synchronized, signals, connections between the signal means and the speeding-up and slowing-down means whereby the former are operated respectively from the latter. 50

5. In combination the tempo lever of a record controlled musical instrument to be synchronized with another device, speed-up and slow-down mechanisms of a synchronizer, signals adjacent the tempo lever, signal control connections between the respective signals and the speed-up and slow-down mechanism whereby the position to 60 which the tempo lever should be moved is indicated by the operation of the signals by the respective speed change mechanisms.

6. In combination the tempo lever of a record controlled musical instrument to be 65 synchronized with another device, speed-up and slow-down mechanisms of a synchronizer, signals adjacent the tempo lever, signal control connections between the respective signals and the speed-up and slow-down mechanism whereby the position to which the tempo lever should be moved is indicated by the operation of the signals by the respective speed change mechanisms. 70

In testimony whereof, I affix my signature. 75

GEO. W. GITTINS,
Administrator of the estate of Heinrich Bockisch, inventor, deceased.
